CLAIM

The ornamental design for a solar stand, as shown and described.

DESCRIPTION

FIG. 1 is a top perspective view of a solar stand; FIG. 2 is a bottom perspective view thereof; FIG. 3 is a front elevational view thereof, a rear elevational view being a mirror image thereof; FIG. 4 is a right side elevational view thereof, a left side elevational view being a mirror image thereof; FIG. 5 is a top plan view thereof; and, FIG. 6 is a bottom plan view thereof.

The broken line showing of rollers and other features is included for the purpose of illustrating environmental structure and forms no part of the claimed design.
